UNITED STATES PATENT OFFICE

LOUIS C. KUEHNER, OF ST. LOUIS, MISSOURI, ASSIGNOR TO HANDLAN-BUCK MANUFACTURING COMPANY, OF ST. LOUIS, MISSOURI, A CORPORATION OF MISSOURI

BURNER

Application filed April 9, 1930. Serial No. 442,762.

This invention relates to a burner intended for use especially in railway hand lanterns which are subjected to severe motion in giving signals, and constitutes an improvement on Patent No. 1,276,417, granted on August 20, 1918, to George H. Rolfs. The invention has for its object the production of a flame spreading burner for a lantern of this kind so formed as to avoid extinction of the flame due to currents of air entering the lantern. The flame spreader surrounds and surmounts the upper end of the wick tube, and includes provision therein for the entrance of air to supply oxygen to a flame burning from the wick, and said flame spreader also includes means for so protecting the air entrance ways as to avoid movement of air therethrough with sufficient force to interfere with the burning of the flame.

The improved flame spreader disclosed herein also is provided with apertures in the end walls thereof which serve a very important function in that they greatly reduce the likelihood that the flame will be extinguished in the ordinary use of the lantern.

Fig. 1 is a top view of my burner in position on a lantern font.

Fig. 2 is a side elevation of a fragment of a lantern font, the burner being shown partly in elevation and partly in vertical longitudinal section.

Fig. 3 is an elevation of the upper portion of the lantern font, the burner being shown partly in elevation and partly in cross-section.

In the drawing, wherein is shown for the purpose of illustration, merely, one embodiment of the invention, A designates a lantern font of any ordinary form, and B designates a burner fitted to said font. The burner includes a wick tube b, within which a wick C is arranged.

At the upper end of the wick tube of my burner a cup-shaped flame spreader D is arranged, this flame spreader comprising a bottom member 1 secured to the wick tube, end walls 2, and side walls 3, the side walls preferably being longer than the end walls, thereby rendering the cup-shaped spreader of elongated shape. In the side walls of the

spreader are apertures 4, preferably of elongated shape, these apertures terminating in proximity to the top edges of said side walls and extending downwardly to points near the bottom of the spreader. The apertures 4 serve to admit air to the interior of the spreader D in a lateral direction through the side walls 3 to supply the necessary oxygen for the support of combustion immediately above the wick of the burner, notwithstanding the fact that the wick terminates at the bottom of the spreader which extends thereabove.

The spreader D acts to spread the flame, due to its extension above the height of the upper end of the burner wick, the flame being drawn to the walls 2 and 3 of the spreader, thereby enhancing the illuminating power of the flame above the spreader.

To avoid the direct passage of air currents through the apertures 4 with such force as might interfere with the steady burning of the flame within the flame spreader, I provide baffle wings 5. These baffle wings extend downwardly and outwardly from the top edges of the side walls 3 of the flame spreader, being inclined away from said side walls so that air may pass beneath them and then upwardly to enter the interior of the flame spreader through the apertures 4. The baffle wings flare outwardly from the top of the flame spreader, as described, preferably downwardly to a horizontal line through the burner at a lower level than the bottoms of the apertures 4, and consequently there is no opportunity for strong currents of air to pass in a horizontal course through the apertures 4, but, on the contrary, all air entering the spreader through said apertures 4 must move in an upward course so as to pass beneath the baffle wings, and such air, by passage in an upward course, assists materially not only in supplying oxygen to the burner flame but also in maintaining a steady flame.

The baffle wings 5 of my burner are preferably provided with apertures 5' so located as to permit the passage of a certain amount of air through the baffle wings when a lantern equipped with my burner is lowered suddenly in giving signals. Therefore, when a lantern is so moved, there can be no sud-

den rush of air through the apertures 4 in such quantity as to interfere with the proper burning of the flame within the flame spreader. As shown in Fig. 3, the apertures 5 are disposed in a lower horizontal plane than that in which the apertures 4 are located. For the purpose of stabilizing the baffle wings so that they may not be bent from their proper inclined positions relative to the side walls of the flame spreader, I provide each baffle wing with a supporting leg 5^a suitably secured to the lower portion of the burner.

The structure which comprises the flame spreader D, baffle wings 5, and legs 5^a is preferably stamped from a single sheet of metal, and this stamping is bent so as to produce a structure of the proper shape. The arrangement of the structure referred to is such that each baffle wing 5 at its opposite ends is provided with inwardly extended flange portions 6, and at each end of the structure the inwardly extended flange portions 6 on the baffle wing at such end of the structure overlaps the inwardly extended flange portion 6 on the baffle wing at the opposite side of the structure, as shown by dotted lines at the points designated by the reference character 7 in Fig. 1. Also, at the opposite ends of the bottom member 1 of the flame spreader D, said bottom member is provided with portions 8 which are bent upwardly and across the top edges of the overlapping flange portions 6, and then downwardly in contact with the outer faces of the outermost flange portions. This arrangement provides the end walls 2 of the flame spreader, and as the portions 8 closely embrace the overlapping inwardly extended flange portions 6 of the wings 5, a very rigid structure is provided.

At the opposite ends of the flame spreader the end walls 2 produced by the associated flange portions 6 and portions 8 are notched, apertured, or otherwise cut away to provide openings 9. These openings are open at the top edges of the end walls 2 of the flame spreader and extend downwardly from said top edges, as shown clearly in Figs. 2 and 3. It has been found that the presence of the openings 9 greatly increases the efficiency of the burner, inasmuch as the likelihood of the flame being accidentally extinguished is materially reduced because of the use of said openings.

While I have described my burner as being intended more especially for use with lanterns, it is obvious that it may be used to good advantage in connection with lamps of various sorts.

I claim:

1. A burner of the character described, comprising a wick tube, a cup-shaped flame spreader secured to said wick tube, said flame spreader having end walls provided with

apertures, integrally formed baffle wings flaring downwardly and outwardly from the upper portions of the side walls of said cup-shaped flame spreader, and supporting means for anchoring the lower ends of said baffle wings to said burner. 70

2. A burner of the character described, comprising a wick tube, a cup-shaped flame spreader secured to said wick tube, the side and end walls of said spreader having apertures therein, said flame spreader including integrally formed flaring baffle wings which extend downwardly from the upper portions of said side walls to points beneath the lower edges of the apertures, and supporting 80 means for anchoring the lower ends of said baffle wings to said burner. 75

3. A burner of the character described, comprising a wick tube and a cup-shaped flame spreader secured to said wick tube, the end walls of said spreader having apertures therein which are open at the top edges of said end walls, integrally formed baffle wings flaring outwardly and downwardly from the upper portions of the side walls of said 90 spreader, and supporting means for anchoring the lower ends of said baffle wings to said burner. 85

4. A burner of the character described, comprising a wick tube, a cup-shaped flame spreader secured to said wick tube, said flame spreader having side and end walls provided with apertures, integrally formed perforated baffle wings flaring downwardly and outwardly from the upper portions of 100 the apertured side walls, and supporting means for anchoring the lower ends of said baffle wings to said burner. 95

In testimony that I claim the foregoing I hereunto affix my signature. 105

LOUIS C. KUEHNER.
